United States Patent Office.

JOHN HARTZELL ZINN, OF HARRISBURG, ASSIGNOR TO HIMSELF AND T. B. WEAKLEY, OF DAUPHIN COUNTY, PENNSYLVANIA.

Letters Patent No. 79,288, dated June 23, 1868.

IMPROVED LINE-HOLDER.

The Schedule referred to in these Letters Patent and making part of the same.

TO ALL WHOM IT MAY CONCERN:

Be it known that I, JOHN HARTZELL ZINN, of Harrisburg, in the county of Dauphin, and in the State of Pennsylvania, have invented certain new and useful Improvements in Line-Holders; and do hereby declare that the following is a full, clear, and exact description thereof, reference being had to the accompanying drawings, and to the letters of reference marked thereon.

In the annexed drawings, forming part of this specification—

Figure 1 is a front view, and

Figure 2 a side view.

The nature of my invention consists in a frame, with a circular flange and a double lever, to hold a rope or wire, which device may be either suspended with a ring, or fastened by screws to a post, or anything else most convenient.

To enable others skilled in the art to make and use my invention, I will proceed to describe its construction and operation.

A represents a frame or plate, made of iron, brass, glass, or any other suitable material, and of any shape desired. This frame has at its upper end a circular or arched flange, B, and at its lower end an L-shaped arm, C, to which latter a double lever, D, is pivoted. The lever D may be either arch-shaped or angled, so that one arm extends on each side of the frame A, above and beyond the corners of the flange B. The tops of these arms, to the lever D, are grooved out, to admit the rope or wire, and may project out, so that when the rope is laid between these prongs it can be drawn or stretched at any angle, and cannot slip off those points.

There is another arm, a, extending perpendicularly on the lever D, pointing towards the concave part of the flange. This is also grooved out, to admit the rope, and extends a little above the corners of the flange B.

By this arrangement it will be seen that when a rope is laid over the arms of the lever, and under the flange, it is securely held by the extended arm a against the corner b of the flange B, and also by the lever to corner c of the flange.

The frame A can be suspended with a ring, or screwed against a post or whatever is most convenient, or it may be suspended by an extension of the frame passing through a hole, and securing it by a nut or screw.

Having thus fully described my invention, what I claim as new, and desire to secure by Letters Patent, is—

The arrangement of the lever D with central arm a, pivoted on the frame A and arm C, in connection with the arch-shaped flange B, all made of iron, brass, or other suitable material, for the holding of rope or wire, substantially as herein set forth and described.

In testimony that I claim the foregoing, I have hereunto set my hand, this 17th day of April, 1868.

JOHN HARTZELL ZINN.
